UNITED STATES PATENT OFFICE.

ROY OVERAND, OF GALESBURG, ILLINOIS.

SELF-LOCKING SASH-FASTENER.

1,148,712.

Specification of Letters Patent.

Patented Aug. 3, 1915.

Application filed April 10, 1915. Serial No. 20,466.

To all whom it may concern:

Be it known that I, ROY OVERAND, a citizen of the United States, and a resident of Galesburg, in the county of Knox and 5 State of Illinois, have invented a new and useful Self-Locking Sash-Fastener, of which the following is a specification.

The invention relates to devices made in two co-acting or interlocking parts, one of 10 which is fixed to the upper and the other to the lower window-sash for the purpose of locking them when both sashes are closed.

The principal object of the invention is to generally improve the construction and 15 increase the capacity, utility and efficiency of devices of this character.

Another object is to provide co-acting members which will automatically interlock when they are brought into engaging pos- 20

25 A further object is to provide a device which cannot be operated, as by a blade, hook or other instrument, from the outside, thereby preventing a trespasser from open-

ing the window. It is another object to provide a device by 30 means of which the sashes will be automatically drawn together as the members interlock, whereby rattling of the sashes will be prevented. Furthermore, the sashes are brought so closely together that it will be impossible to insert even a thin blade be- 35

40 between them. That the mechanism constituting the means for carrying out the objects above recited be durable, strong and simple, is a prime requisite, and to provide such means constitutes another object.

45 Minor objects will presently appear; some of these will be obvious and others will be particularly pointed out.

The invention consists, substantially, in the constructions and combinations particu- 50 larly pointed out.

45 In the accompanying drawings, which illustrate a preferred embodiment of my invention: Figure 1 is a top plan, showing the complete invention as in use; Fig. 2, a transverse section, partly in elevation, the 55 plane of section being taken substantially in the line 2— in Fig. 1; Fig. 3, a perspective detail of the cam-ring and actuating lever; Fig. 4, an elevation of the latch-engaging member or keeper, seen in the line 4—4, Fig. 1; Fig. 5, a bottom plan of the

same member; Fig. 6, a top plan detail of one of the base-plates; Fig. 7, a front elevation of the integral latch and spring-box; and Fig. 8, an inverted plan thereof.

Coming now to a detailed description of the drawings, in which the same reference numeral uniformly indicates the same part, 2 indicates a base-plate having an ear 3 at each of its ends, each ear having an aperture 4.

5, 5' are bosses or supports, the former acting also as a fulcrum or rocker for the latch and spring-box.

6 indicates a central aperture.

7 (Fig. 3) designates a combined cam-ring (8) and actuating lever 9. The ring is provided with a cam-face 10, a horizontal face 11, and shoulders 12 and 13.

14 (Figs. 7 and 8) designates a latch, one end of which constitutes a spring-box 15 provided with a conical central aperture for the reception of an inverted screw 17 upon which it both pivots and tilts or rocks. The head of said screw engages the aperture 6 in the plate 2 and its threaded upper end engages the threads of an aperture in a cap 18 provided with ears 19 having each an aperture 20 for the reception of screws 21 which pass also through the apertures 4 in the base-plate 2 and are threaded into the upper rail of the sash 22.

23, 24 indicate respectively upper and lower panes, secured by putty 25 to the sashes.

26 indicates the latch-stem having at its terminal a lateral projection 27 and an up-standing projection 28. Its extremity is preferably rounded off to provide a smooth-contact face 29, and the inner face of the projection is similarly fashioned to provide a cam-face 30. Coiled around the screw 17 is a latch-return spring 51 which acts both torsionally and by axial expansion. One of its ends engages an aperture 31 in the bottom of the box 15 and its other end engages an aperture 32 in the cap 18.

33, 33 indicate oppositely disposed arcuate grooves in the lower face of the spring-box.

34 indicates a base-plate each end of which is apertured.

35 indicates a latch-receiver or keeper having at each end an ear provided with an aperture registering with the corresponding one in the plate 34. 36, 36 designate screws

passed one through each pair of said apertures and threaded into the lower rail of the upper (or outer) sash, 37.

38 indicates the back, which is a flat plate.

39 indicates an inclined way, undercut at 40.

41 indicates a projection affording a shoulder 42, and 43 indicates a transversely arranged recess for the reception of the latch-stem 26.

44 represents a recess for the projections 27 and 28.

The operation is as follows: Assume the parts to be in the relative positions shown by full lines in Fig. 1, which is the locked one. To release the interlock the lever 9 will be drawn (against the resistance of the spring) to the dotted line position α , Fig. 1, by which movement the spring-box bottom will tilt or rock on the boss 5 to throw the locking end of the latch-stem 26 downward, the movement thereof being caused by the cam-face 10 bearing upon said end of the lever.

When the shoulder 12 strikes the stem 26 the element 14 will be moved rotatively with the element 7. A further pull on the lever 9, as indicated at γ , same figure, will bring the grooves 33 in the spring-box bottom into position to receive the bosses 5, 5', whereupon the axial expansion of the spring 51 will force said box and the stem 26 down onto the plane faces of the base-plates 2 and 34. It may here be stated that if preferred the plate 34 may be dispensed with. The operator will still hold the lever and will simultaneously raise the sash 22 to bring the stem 26 into the inclined way 39 and the projection 27 into the undercut 40 groove 40. He will then release the lever 9 and raise the sash to any position desired, the stem 26 and projection 27 sliding upward in and out of their respective channels.

To lower the lower sash from the elevated position just described and to lock it in the position shown in full lines in Fig. 1, the lower one is merely to be drawn down, whereby the stem 26 and projection 27 will automatically enter and pass down their respective ways. When the stem has reached a horizontal plane below that of the point 46 (Figs. 4 and 5) the spring 51 will automatically act, by torsion, to throw it backward over the face of the projection 41. While the above movements were progressing the bosses 5, 5' were lying in the grooves 33 and the bottom of the element 14 resting on the base plates. When said stem has moved entirely past the shoulder 42 the beveled or inclined terminals of the grooves 33 will move upward on the bosses 5, 5' to raise the element 14 to the full line position shown in Fig. 2, the projection 28 lying locked in the recess 44, the stem 26 against

the shoulder 42, and the spring axially compressed.

The cam-face 30 in moving as last described will pass behind the curved or cam-face 50 of the shoulder 42 and thus draw the sashes tightly together. The projection 27 will move in contact with the proximal wall of the undercut groove 40 and tend to draw said sashes toward each other as the sash 22 is being lowered.

It is to be understood that the several instrumentalities which enter into my invention may be variously constructed, arranged and organized, and that I do not contemplate the scope of the invention as limited, (except where a limitation is particularly noted in the several claims,) to the specific structure shown and described, but consider it as covering all such changes as fall within the general idea thereof, considered in its broadest aspect.

Having thus described the nature and characteristics of the invention, I claim as new the following, to-wit:

1. In a sash-lock, a pivoted latch one end of which has a lateral and a vertical projection and the other end of which constitutes a spring-box, a spring arranged in said box and adapted to impart pivotal movement in one direction to said latch, and a latch-receiver having an undercut groove and an inclined way for the passage of said projections respectively and having also recesses into which said projections pass.

2. In a sash-lock, an integral, tilttable spring-box and latch-stem, a spring coiled in said box and one of its ends secured thereto, means for securing its other end, a cam-faced element adapted to turn said box and stem rotatively and to tilt them, and a latch-receiver adapted for engagement by said stem.

3. In a sash-lock, a base-plate having spaced bosses, a pivotally mounted spring-box normally resting on said bosses, and provided with arcuate grooves in its lower face, said box having a latch-stem integral therewith, means for rotatively moving said spring-box and thereby said latch-stem to bring said grooves into position to receive said bosses and thereby permit the spring-box and latch stem to move to a lower plane, means for forcing them to such lower plane, and a latch-receiver adapted for engagement by said stem.

4. In a sash-lock, a latch both pivotally and tiltably mounted, a latch-receiver having an inclined way adapted for the passage of said latch whereby to move it pivotally and having also a locking projection forming one wall of a recess, means for tilting said latch to permit it to pass beneath said projection, and means for causing said latch to enter said recess.

5. In a sash-lock, a latch receiver having

an inclined way and an inclined undercut groove communicating therewith, there being a projection at the relatively inner end of said way and a latch-locking recess at the 5 relatively inner end of said projection.

6. In a sash-lock, a latch-receiver, an integral spring box and latch-stem capable of being tilted, a manually actuatable rotatory element having a cam face, said rotatory ele-

10 ment adapted to impart rotatory movement in one direction to said integral element, and to tilt it, and a spring arranged in said spring-box and adapted to impart the same movements in the contrary direction to said integral element, said receiver provided

15 with portions adapted for sliding contact by said latch-stem and provided with other portions adapted for locking engagements therewith.

20 7. In a sash-lock, a latch-receiver provided with an undercut groove and with an inclined way, and provided also with a recess one wall of which is afforded by a shoulder, and a spring-controlled latch having a projection adapted to move in said groove, its end adapted to move in said way, and one of its portions adapted to rest in said recess and to lock against said shoulder.

25 8. In a sash-lock, a latch-receiver provided with a recess one wall of which is formed by a projection, an integral element comprising a spring-box and latch, means on which said integral element is pivotally mounted, a rocker on which said integral element is adapted to rest, means for tilting or rocking it thereon, and a spring arranged in said box and adapted to impart rotative movement to said integral element to de-

30 press said latch below said projection and into said recess.

9. In a sash-lock, a base-plate having a pair of bosses, a spring-box seated on said bosses and having arcuate grooves adapted 45 for the reception of said bosses, said spring-box including a latch-stem, a cap, a screw or the like connecting said plate and cap, a ring

provided with a cutaway portion one wall of which is a cam-face, a spring coiled around said screw and arranged in said box, 50 one of its ends secured to the box and the other to the cap, said box arranged in said ring and the latch-stem in said cutaway portion, said ring having an actuating lever whereby it may be turned to cause said latch 55 and spring-box to tilt on one of said bosses and to bring said grooves into position to receive the latter, and a latch-receiver having portions adapted to be passed beneath by said latch-stem as the latter is tilted down- 60 wardly and to be engaged thereby to interlock therewith when they are tilted upward.

10. In a sash-lock, a base-plate having a pair of bosses, a spring-box normally resting on said bosses and having a latch-stem, 65 said box provided with grooves for the reception of said bosses, manually actuatable means for bringing them into position to receive said bosses or for removing them therefrom, a spring arranged in said box 70 and adapted to impart rotatory and downward movement to said box and stem, and a latch-receiver adapted to be engaged by said stem in all of said movements.

11. In a sash-lock, an integral spring-box 75 and latch-stem capable of being tilted, a spring for imparting pivotal movements thereto, a cam-ring adapted to impart both pivotal and tilting movements to said box and stem, and an element adapted for lock- 80 ing engagement by the latch.

12. In a sash-lock, an integral spring-box and latch-stem capable of being tilted, a spring for imparting pivotal movements thereto, a cam-faced element for imparting 85 both pivotal and tilting movements to said box and stem, means for imparting upward movements to said box and stem, and an element adapted for locking engagement by said latch. 90

In witness whereof I hereunto sign my name, at Galesburg, in the county and State above written, this fifth day of April, 1915.

ROY OVERAND.
